J. F. Harley

United States Patent Office.

J. F. HARLY, OF KIPTON STATION, OHIO.

Letters Patent No. 99,314, dated February 1, 1870.

IMPROVEMENT IN STREET-LAMPS.

The Schedule referred to in these Letters Patent and making part of the same.

To all whom it may concern:

Be it known that I, J. F. HARLY, of Kipton Station, in the county of Lorain, and State of Ohio, have invented certain new and useful Improvements in Street-Lanterns; and I do hereby declare that the following is a full and complete description of the same, reference being had to the accompanying drawings, making part of this specification.

Objective.

This invention relates to a street-lantern, constructed of two concavo-convex glasses, secured in metallic rims or bows hinged to each other, which, on being closed, presents a flattened globe-like lantern.

A further improvement consists in so mounting the lantern on the lamp-post that it may turn in the direction of the wind, thereby presenting to it only a thin or narrow side, thus offering but little surface directly to the wind, and, therefore, is not liable to be blown down during storms.

Drawings.

Figure 1 is a front view of the lantern.

Figure 2 is a side view.

Like letters of reference refer to like parts in the different views.

Description.

This lantern is constructed of two glass sides, A, B, fig. 2, each of which is in shape a concavo-convex, similar to a watch-crystal.

Said glasses are secured in rims or bows C D, which are connected to each other by a hinge, E, fig. 1, whereby one of the two sides may be opened to obtain access to the inside, but which, when closed, are fastened by the lock F.

At the lower side of the lantern is an air-passage, G, for the admission of air to the burner.

Corresponding to the opening below, is an opening, H, at the top, for the escape of the heated air and gas.

Said opening or vent is protected from the rain, &c., by a cap, I.

The globe or lantern is secured to the top of the

post J, by means of the curved arms K, one section of the lantern being permanently attached to the upper part of the arms, through the intervention of the sleeve A', whereas the lower part of the arms are attached to the collar L, loosely fitted to the post, thereby allowing the lantern to rotate on the post and around the tube B' of the burner.

The peculiar advantages resulting from a street-lantern constructed as above described, are: More light from a given-sized burner will be thrown off, for the reason that the lantern has a larger amount of open surface for the transmission of the light from the lamp or gas-jet within; the glass part of the lantern being made up of two pieces only, whereas those in ordinary use are made up of many pieces, held in place by a frame, in which the several pieces of glass are set, said frame, to a great extent, obstructs the passage of the rays of light, hence much of the light is lost. Also, the street-lanterns in ordinary use are of a square form, thereby presenting a broad surface to the winds, which causes them not unfrequently to be blown down, which accident cannot happen to a lantern constructed as above described, as the lantern will turn with the wind, thereby presenting its narrow side to it, and thus offer but little resistance to its force, and therefore escape being blown down. It is also much easier kept clean, as there are no corners for the lodgment of dirt and dust, and therefore can be kept clean and bright with less labor and expense.

What I claim as my improvement, and desire to secure by Letters Patent, is—

1. A lantern, constructed of two concavo-convex sections, A, B, in the manner substantially as described, and for the purpose set forth.

2. A lantern, constructed of the sections A, B, provided with a cap, I, sleeve A', arms K, and collar L, and arranged in connection with the post J, so as to revolve thereon in the manner as described, and for the purpose set forth.

J. F. HARLY.
